UNITED STATES PATENT OFFICE.

WILLIAM R. LEIGH, OF NEW YORK, N. Y.

CAMP-STOOL.

1,284,377.

Specification of Letters Patent. Patented Nov. 12, 1918.

Application filed January 13, 1915. Serial No. 1,919.

To all whom it may concern:

Be it known that I, WILLIAM R. LEIGH, a citizen of the United States, residing at the city of New York, borough of Manhattan, in the county and State of New York, have invented certain new and useful Improvements in Camp-Stools, of which the following is a full, clear, and exact specification.

My invention relates to improvements in folding chairs and the same has for its object more particularly to provide a simple, efficient and reliable folding camp chair, which is composed of few parts and is easy to assemble for use, and to dismount to permit of packing and transportation.

Further, said invention has for its object to provide a camp stool comprising a folding support, and a detachable seat having integrally-formed pockets at its edges adapted to receive the upper ends of said support.

Further, said invention has for its object to provide a camp chair having a seat formed of an integral piece of material and provided at its edges with a plurality of integrally-formed projecting members which are adapted to be folded downwardly and inwardly and permanently secured along their edges to the conforming edges of the seat proper.

To the attainment of the aforesaid objects and ends, my invention consists in the novel details of construction, and in the combination, connection and arrangement of parts hereinafter more fully described and then pointed out in the claims.

In the accompanying drawings forming part of this specification, wherein like numerals of reference indicate like parts,—

Figure 1 is a perspective view showing one form of camp stool constructed according to and embodying my said invention;

Fig. 2 is an enlarged detail face view of the seat proper with its end portions extended prior to the securement thereof to the body portion of the seat to form the pockets for the support-members;

Fig. 3 is a bottom view of the seat with the end flaps riveted to the body portion of the seat to form the pockets;

Fig. 4 is an enlarged detail side view showing one end of the seat with the pocket thereon, and the upper portion of a support disposed within said pocket, and

Fig. 5 is a detail perspective view showing the underside of one end of the seat and the pocket thereon with the end of a support disposed therein.

In said drawings 10 designates the chair as a whole comprising a folding support 11 consisting of three members 12, 12 which are secured together by bolts 13. The said members 12, 12, when folded together, form substantially a cylindrical structure.

14 denotes the seat proper which is preferably made of heavy leather or other suitable pliable material, and is here shown as triangular in outline and provided at each of its corners with a narrow, radial end portion 14^a having parallel longitudinal edges. From each end portion extends an integrally-formed foldable portion or flap 15, formed as a prolongation of its end portion 14^a, and extending beyond the geometrical outlines of said seat proper 14 and the end portions 14^a thereof. The foldable portions or flaps 15, 15, and the radial end portions 14^a, 14^a of the seat 14 are provided with registering apertures 16, 17, respectively, for the reception of rivets 18 which are adapted to extend through the apertures 16, 17 when said foldable members or flaps 15, 15 are folded over against the underside of the seat 14 and secured thereto to form the pockets 19.

In connection with my improved seat it is to be noted particularly that when the same is in use the strain upon the seat is directed principally against the corner or end portions 14^a where the same join with the edges of the foldable portions 15, and that by forming said foldable portions or flaps 15 integrally with the body portion 14 of the seat, and thence riveting said foldable portions or flaps at their opposite edges to the corresponding edges of the end portions of the seat, a strong, firm pocket is provided for the reception of the upper ends of the supporting members 12, and which pocket will not give way or be liable to tear as a result of use.

While I have shown my seat as formed triangular in outline it will nevertheless be quite obvious that the outline of the seat may be varied, and still permit of the embodiment of my invention therein.

Having thus described my invention, what I claim and desire by Letters Patent is:—

1. In a folding chair, a seat formed of pliable material and having a body portion of polygonal outline, a plurality of end portions extending radially from the corners of said body portion, and flaps formed as prolongations of said end portions folded downwardly and inwardly within the geometrical

outline of said end portions, and secured along their opposite, longitudinal edges to the corresponding edges of said end portions to form pockets, substantially as specified.

2. In a folding chair, a seat having a body portion of triangular outline formed of pliable material, narrow end members extending radially outwardly from the corners of said body portion, and flaps formed as prolongations of said narrow end members

folded downwardly and inwardly within the geometrical outline of said end members, and riveted along their opposite, longitudinal edges to the underside of said end members to form pockets, substantially as specified.

3. In a folding chair, a seat formed of pliable material and having a body portion of polygonal outline, a plurality of end por-

tions extending radially from the corners of 20 said body portion and having parallel longitudinal edges, and flaps formed as prolongations of said end portions and having parallel longitudinal edges, said flaps being folded downwardly and inwardly and secured along 25 their parallel longitudinal edges to the corresponding edges of the under surfaces of said end portions to form pockets, substantially as specified.

Signed at the city of New York, in the 30 county and State of New York, this 24th day of July, one thousand nine hundred and fourteen.

WILLIAM R. LEIGH.
